LADDER JACK

Ernest L. Coble, East Cleveland, Ohio, assignor
to The Star Welding & Manufacturing Com-
pany, Inc., Cleveland, Ohio, a corporation of
Ohio

Application January 3, 1948, Serial No. 407

3 Claims. (Cl. 248—238)

1

This invention relates to a jack adapted to be mounted on a ladder at desirable heights at one side of a wall or other structure. Two of these jacks are adapted to be mounted on spaced ladders at the same level and support a scaffold, on which one or more workmen may stand, walk or sit.

One object of the invention is to provide an improved jack of this type constructed to engage parts of a ladder to insure safety to the workman and eliminate tipping, wobbling or vibration of the scaffold incident to movement of the workman thereon.

Another object of the invention is to provide an improved jack of this type having a supporting member on which one end portion of the scaffold rests, which member co-operates with the corresponding supporting member on the other jack to prevent tipping or distortion of the scaffold intermediate the jacks incident to the operations or traverse of the workman on the scaffold.

Another object of the invention is to provide an improved jack of this type having spaced pairs of fixedly related supporting members arranged to readily engage and disengage the ladder rungs and ladder side rails which differ in size and spacing.

Another object of the invention is to provide an improved jack of this type the parts of which are constructed to adequately support heavy loads.

Another object of the invention is to provide an improved jack of this type consisting of a frame member adapted to engage a rung and side rails of a ladder and chains each adapted to engage a ladder rail and another ladder rung, each chain having a terminating hook member shaped to insure a positive connection with an intermediate chain link.

A further object of the invention is to provide an improved jack of this type having a base member provided with supporting elements or devices adapted to engage a rung and side rails of a ladder, converging side members and chains connected to the outer ends of the side members and adapted to engage another rung and adjacent side rails of the ladder, whereby the jack is braced against movement relative to the ladder.

Other objects of the invention will be apparent to those skilled in the art to which my invention relates from the following description taken in connection with the accompanying drawings, wherein

2

Fig. 1 is a fragmentary elevation showing two spaced ladders and jacks, each embodying my invention mounted thereon and supporting a scaffold.

5 Fig. 2 is a section on the line 2—2 of Fig. 3.

Fig. 3 is a section on the line 3—3 of Fig. 2.

Fig. 4 is a section on the line 4—4 of Fig. 3.

10 Figs. 5 and 6 are sections on the lines 5—5 and 6—6, respectively, of Fig. 2.

Fig. 7 is a view similar to Fig. 2, but showing the jack mounted on the inner side of a ladder.

Fig. 8 is a detail view.

In the drawings, 1 indicates as an entirety, the jack mounted on a ladder A. As shown in Fig. 15 1, two jacks 1 are shown mounted on spaced ladders A, A, to support a scaffold B, the ladders being related to a wall or other structure (not shown), on which a sign or other device is to be mounted or which is to be repaired, painted, or otherwise conditioned. Each jack 1 consists of a frame 2 of V-shape (that is, forms a substantially isosceles triangle) and a pair of chains 3, 3, later referred to. The frame 2 is formed from sections of metal bars, each disposed vertically and welded into a rigid assembly. The frame 2 consists of the following: 4 indicates a base member extending beyond the opposite outer sides of the side rails of a ladder A. 5

20 25 5 indicates a pair of converging side members connected at their inner ends to end portions of the base member 4. The outer ends of the side members 5 are rigidly connected together by a bolt or rivet 6. A vertically disposed member 7 is interposed between the outer ends of the side members 5 and secured thereto by the bolt 6. The member 7 serves as a stop for the scaffold B and a connecting device for the outer ends of the chains 3. As shown the member 7 extends upwardly to a point slightly above the plane of the upper surface of the scaffold B,

30 35 40 45 50 55 and the chains 3 are connected by a link to the upper end of the member 7 so as to clear the scaffold and permit the latter to be positioned and removed without engaging the chains 3. 8 indicates supplemental side members, disposed outwardly of the side members 5, 5, each member 8 being connected at its outer end to the adjacent side member 5 and to the adjacent outer end of the base member 4 to reinforce the latter.

50 Each supplemental member 8 extends beyond the remote or outer side of the base member 4, as shown at 8a, so as to overlap the adjacent side rail a for a purpose later set forth. 9 indicates a cross member disposed substantially midway the inner and outer ends of the side

members 5 and connected at its opposite ends thereto. The cross-member 9 co-operates with the base member 4 to prevent deflection of the side members 5 laterally or downwardly between their opposite ends.

10, 10, indicate a pair of members mounted on the base member and extending outwardly thereof and adapted to removably engage a selected rung b of the ladder A and co-operate with the base member 4 to connect and support the inner end of the frame 2 to the ladder. Each rung engaging member 10 is spaced from the adjacent extension 8a so that they may be disposed at opposite sides of the adjacent rail a, of ladders having rails variably spaced. Each member 10 is of inverted U-shape, its inner side leg being provided with an extension 10a which is welded face-to-face to the outer side of the base member 4. The intermediate or curvilinear portion 10b of each member 10 is struck on a large radius, as compared to that of the ladder rung b, so that such portion will extend a considerable distance above the base member 4 and the outer leg of the member will be spaced a considerable distance from its inner leg. As shown, the curvilinear portions 10b of the members 10 engage the rung b and the lower horizontal edge of the base member 4 engages the adjacent side edges of the ladder rails a to connect the inner end of the frame 2 to the ladder. By the form of construction of the rung engaging members 10, as above set forth, provision is made to (a) adequately space the fulcrum point of contact thereof with a ladder rung above the lower edge of the base member 4, (b) to provide for variable fulcrum points on curvilinear portions 10b arranged to engage rungs b mounted in side rails a which vary in thickness (measured between their inner and outer side edges), when the jack is supported on the outer side of the ladder (see Fig. 2) or its inner side (see Fig. 7) and (c) facilitates the operation of mounting the frame 2 in position on the ladder A and its removal therefrom.

11 indicates a sill rigidly mounted on the frame 2 in a plane which bisects the angle formed by the side members 5, 5, and extending from the base member 4 to the member 7. The upper surface of the sill 11 is disposed in a plane above and parallel to the frame 2 and is engaged by the end portion of the scaffold B to support it horizontally from side edge to side edge and out of engagement with the side members 5, while permitting it to sag perpendicularly due to the weight of the workman and/or equipment on the scaffold as shown in dotted lines in Fig. 4. Accordingly, danger of the scaffold engaging the side bars 5, which, being disposed at an inclined angle, would cause wobbling, distortion or inclination of the scaffold, is entirely eliminated and any mishap to the workman or equipment on the scaffold is likewise avoided. The sill 11 also reinforces the frame from end to end.

By preference I provide two chains 3 each adapted to be wrapped around one of the rails a and above an adjacent rung b disposed above the rung b engaged by the frame 2. In this arrangement the chains 3 co-operate with the member 4 and members 10 to support the outer end of the frame 2 and hold the latter against swing-

ing movement in its plane. The outer end of each chain 3 is provided with attaching device 12, one end of which is provided with an eye 12a engaging the terminating link of the chain; the opposite end of the device 12 is provided with a hook the entrance opening of which is of a predetermined size to receive one side bar of a link, so that the hook cannot be engaged with the chain in any other manner. This form of hook insures its safe connection with an intermediate link of the chain 3, as shown in Fig. 6 and eliminates carelessness on the part of the workman in making such connections in mounting the jack on a ladder.

What I claim is:

1. A ladder jack for a ladder comprising a frame having a base member adapted to engage the ladder rails and extending beyond the opposite outer sides thereof, converging side members connected at their inner ends to said base member intermediate the ends thereof and connected together at their outer ends, a supplemental side member connected to the outer side of each of said converging side members intermediate its opposite ends and the adjacent outer end of said base member and provided with an extension extending outwardly of said base member and adapted to be disposed in overlapping relation to the outer side of the adjacent ladder rail, rung engaging members secured to the outer side of said base member inwardly of the ladder rails and extending upwardly and outwardly from said base member for engagement with a ladder rung and arranged to co-operate with said base member to support the latter in engagement with the ladder rails, and chains connected at their inner ends to the outer ends of said converging side members, the outer end portion of each chain being adapted to be wrapped around one of the ladder rails in engagement with a rung above the rung engaged by said rung engaging members.

2. A ladder jack as claimed in claim 1 wherein a vertically disposed member is connected at its lower end to the outer ends of said converging side members and extends upwardly therefrom and its upper end forms a connection for the inner ends of said chains.

3. A Jack as claimed in claim 1 wherein is provided a sill connected at its opposite ends to said base member and the outer ends of said converging side members and extending in a plane to bisect the angle formed by the latter members, the upper surface of said sill, from end to end thereof, being in a plane above and parallel to the upper surfaces of said converging side members.

ERNEST L. COBLE.
